UNITED STATES PATENT OFFICE.

OTTO DREYER, OF ESSEN-ON-THE-RUHR, GERMANY.

DEVICE FOR PROTECTING ELECTRIC CIRCUITS FROM OVERHEATING.

Application filed April 25, 1924, Serial No. 708,995, and in Germany February 29, 1924.

The invention relates to devices for protecting electrical circuits from over-heating of the type whereby the circuit which is in danger is disconnected by means of an interchangeable releaser, which consists essentially of a sleeve or casing having a pin-switch or contact rod which is soldered therein with easily fusible material, and, when the solder softens, is pressed forwards by means of a spring and thereby initiates the process of disconnection.

In the known devices of this type the releaser must in general be replaced by a new releaser after each time it has come into operation, i. e. it must be exchanged. According to the present invention, the necessity for this exchange is avoided, by making the releaser of similar form at both ends, and in such a manner that, after once having come into operation, it can be used again by simply reversing it. To this end the casing of the releaser is provided at both ends with openings for the passage of the correspondingly long contact rod, and the spring which acts on the latter is arranged externally of the casing, in such a manner that it is strained when the releaser is inserted and tends to press the contact rod into the opposite end position. It is recommended that the casing which contains the contact rod should be formed as a piece of tube open at both ends, which is either itself capable of being inserted in and held by the heating coil which surrounds it or is combined with the latter to form a cartridge which can be inserted as a unit and can be fitted in a small porcelain case having a screw cap of the same or similar construction as for the known safety cartridge fuses.

The opposing contact with which the contact rod co-acts can be arranged either at the bottom of this casing or on its screw-cap or near the latter. When, in particular, only a limited space is available, as, for example, when arranged in a closed fuse-box, it is recommended that the opposing contact should be arranged on the inside of the cover of the box, in which case the contact rod, or a connecting member actuated by it, must pass through an opening provided in the screw cover of the casing. Such a compact form of construction can be obtained in this manner that the complete protecting device can be built in the form of the usual safety elements and fitted be-

side or between these in the ordinary fuse boxes.

Various constructional embodiments of the invention are illustrated by way of example in the accompanying drawing in which,

Fig. 1 shows in longitudinal section a temperature-protecting-element for currents of small strength,

Figs. 2 and 3, a modified form of construction of the head of the plug of the protecting element of Fig. 1,

Figs. 4 and 5 show respectively the arrangement of the protecting element according to Fig. 1 in combination with two normal safety elements in one fuse box, in section and in plan, the cover of the box being swung open and partly shown in Fig. 5,

Fig. 6, a diagram of connections for the protecting device according to Figs. 1-3,

Fig. 7, a form of protecting element for currents of greater strength, and

Fig. 8 the special form of plug-in releaser for protecting elements according to Fig. 7.

Referring now to the embodiment illustrated by way of example in Fig. 1 of the drawings, 1 is the socket which is made of porcelain or other suitable insulating material, and 2 is the heating coil which is traversed by the current in the circuit which is to be protected. The coil 2 possesses essentially the external form of a safety cartridge fuse and is held fast in the casing, so that it is easily interchangeable and electrically connected, in the same manner as the latter by means of the plug-head 4 which contains, as usual, a sheet-metal cap 3 having an Edison-thread. The current supply takes place by means of the terminal 5 through the screw-socket 6 and the screw cap 3 to a metal casing which encloses the heating coil and to which the outer end of the heating coil is soldered. The inner end of the heating coil is electrically connected, on the other hand, with the metal sleeve 7 which is rigidly connected with the heating coil by means of the flanges 8, 8 and the end plates 9, 9 which latter are of insulating material. The releasing-pin 10 is guided in and closes the central, restricted portion of the metal sleeve 7 and is soldered therein by means of an easily fusible metal while its enlarged ends 10^a and 10^b are guided in the wider part of the sleeve 7, and, in the position of rest illustrated, the lower of the two

- ends, namely, 10^a projects out of the sleeve. From the sleeve 7 the current flows through the lower flange 8 and a foot-ring 11 which is held in the socket 1, to the terminal 12.
- 5 In the ring 11 and guided by it there is fitted a plate 15 which is movable therein and is acted upon by the spring 14 which tends to press the releasing pin upwards but is ordinarily prevented from doing so by 10^a the soft-soldered joint. The upper end 10^a of the releaser projects into an opening 16 provided in the plug-head 4 where at a certain distance from the end 10^a is also situated the opposing contact 17, which is 15 arranged, for example, on the cover of the pertaining fuse-box, and which, as may be seen from the corresponding diagram of connections, Fig. 6, is connected also with the second pole of the current leads.
- 20 If now, owing to inadmissible heating up of the current consumer or of the heating coil, the soldered joint softens, the releasing-pin 10 is pressed upward by the action of the spring 14 until, on touching the 25 opposing contact 17, it short-circuits the supply leads to the current consumer and thereby causes the fuses 18, 19 to blow, that is to say it cuts off the circuit which is in danger. When the circuit has been disconnected the entire heating coil can easily be taken out after the plug-head 4 has been unscrewed; and, assuming that the soldered joint has meanwhile cooled down sufficiently and become fast, can be replaced by inserting it again in the element in an inverted position, that is with the end of the contact rod which has protruded from the top towards the bottom, and fixed by screwing on the plug head, whereby the spring 14 is 35 40 simultaneously again compressed. The device is then, after any fuses which may have blown have been replaced, ready for use without further trouble.
- In order to avoid making contact with 45 the upwardly projecting live end of the releaser when screwing the plug-head on again, it is advantageous not to allow the releasing-pin itself to pass through the plug head, but as is shown in Figs. 2 and 3, to arrange an intermediate contact member 20, which is fitted movably in the plug head 4 and is normally held by the action of the spring 21 in the position illustrated in Fig. 2, that is, it is held in the drawn-in position, at the same time it is of such short dimensions that it does not touch the upper end of the releasing-pin, and therefore is not alive, so that the plug-head can be screwed tight without danger. If, however, the releasing-pin advances on the softening of the soldered joint, it first makes contact with the intermediate member 20 and presses it forward against the action of the spring 21, as shown in Fig. 3, until the latter makes contact with the opposing contact 17 which

is fitted on the cover of the safety element, whereby the endangered circuit is disconnected.

With the compact construction of heating coil and re-usable releaser illustrated in 70 Figs. 1-3, the whole device, as may be seen from Figs. 4 and 5, may be easily and advantageously employed together with the usual elements for the two circuit protectors 18, 19 and may be suitably fitted between 75 them in a common fuse-box 25; on the cover 26 of which the opposing contact 17 is fitted. The latter is connected by means of a spring metal strip 27 with the contact 28 of the other pole, which is fixed in the lower part 80 of the box, and against which its springs, as shown in Fig. 4, when the box is closed thereby conducting the electric potential to the contact 17. If however, the cover 26 be raised the contact at 27, 28 is broken and 85 the metal parts fastened to the cover become dead, so that it is possible to put the protecting device into order again without danger. Whether the device has operated and 90 must be re-set, can easily be ascertained on raising the cover, by the intermediate connecting member 20 projecting out of the plug-head 4, while the condition of the two adjacent fuses can be ascertained in the usual manner by means of the indicating plate of 95 the cartridge fuse which is visible through the sight hole of the plug.

Again, the contact upon which the temperature releaser acts, particularly in the case of safety elements for currents of greater strength, instead of being arranged outside the element, can in some cases be arranged in its foot, as is illustrated by way of example in Fig. 7, when, on the softening of the soldered joint, the contact between the two parts 31, 32 is broken by the spring 30. The construction illustrated in Fig. 7 is however also different from that of the first example in so far as the sleeve 7 of the temperature releaser is not fixed in the heating coil but is held loosely, so that it is capable of being pushed in, in a bush 34 which is fixed in the coil. In this case the spring 30 tends to hold the releaser 7, 10 in the pushed-in position, which is limited in the upward direction by the projecting part 35 of the bush 34. Thus, it is no longer the complete heating coil together with the releaser which is insertable but the latter is itself arranged so that it is capable of being inserted in the heating coil, which can be removed for this purpose after the plug-head has been unscrewed.

This arrangement possesses also the special advantage that the actual insertable temperature releaser is extraordinarily simple, as may be seen from Fig. 8, and can easily be exchanged if necessary for another similar releaser, having its soldered joint made with 120 more easily or more difficultly fusible metal,

according as it is desired that the circuit to be protected should be disconnected earlier or later. By this means one and the same device may easily and without great expense 5 be made suitable for different strengths of current. Independently thereof, the protecting device can also, by changing the heating coil which is in itself interchangeable, be made to suit the temperature limit desired 10 at any time.

Claims:

1. In a self-soldering device for protecting electric apparatus, and which is controlled by the heat developed by the current 15 for said apparatus, in combination, an insulating case, comprising a body and a cover detachably connected therewith, said cover having an opening, an axially perforated heat coil in said case in cartridge form, said 20 coil being disposed mutually within the casing and its cover and removably held between the same, a guide tube within the axial perforation of said cartridge, a releaser pin, adapted for longitudinal reciprocation within said guide tube, in line 25 with the opening in the cover but normally securable therein in an end position by a thin layer of heat responsive material of predetermined melting point, in which position 30 one end of the pin is retracted relative to the opening in the cover, means urging said releaser pin from the one end position into the other relative end position, whereby upon the release of the pin the pin will be 35 moved to project its first named end relative to said opening in the cover, said guide tube together with said releaser pin being readily reversible, end for end in said casing and binding posts connected to the ends of the 40 coil.
2. In a safety device of the character set forth, in combination with a base carrying two stationary contact members, a third contact member independent of said base, a 45 releaser cartridge, comprising an axially perforated heating coil unit removably mountable on said base in electric series contact with said two stationary contact members, a sleeve mounted in said axial coil perforation, a double-ended releaser pin operable within said sleeve, a heat controlled solder joint between said sleeve and said pin adapted to normally retain said pin in its 50 inoperative end position, and means urging said pin into its operative end position in contact with said third contact member upon said solder joint being broken by excess heat in said coil.

3. In a safety device according to claim 2, an intermediate member in axial alignment with, and operable by, said releaser pin, interposed in normally spaced relation between said releaser pin and said third contact member, and means, weaker than said pin-urging means, normally retaining said 65 intermediate member out of contact with said third contact member.

4. In a safety device of the character set forth, in combination with a base carrying two stationary contact members for the one circuit main, a third contact member for the other circuit main, a releaser cartridge, comprising an axially perforated heating coil unit removably mountable on said base by screw-threaded engagement in electrical 70 series contact with said two stationary contact members, and a cover for said coil unit presenting a top depression merging into a central perforation in alignment with said coil perforation, said third contact member 75 overhanging said top depression, a metal sleeve in said axial coil perforation, a releaser pin presenting identical contact extremities operable within said sleeve, a fusible joint between said sleeve and said pin, 80 said joint being broken upon the heat of said heating coil exceeding a predetermined 85 degree, and said pin normally relatively retained in its inoperative end position by said fusible joint, and means tending to force said pin through said central cover perforation into contact with said third contact member upon said fusible joint being broken.

5. In a safety device according to claim 95 4, a case housing said base and cartridge, a cover for said case, and said third contact member being so mounted within said case that it is automatically cut out of the circuit on opening of said cover and cut in on 100 closing thereof.

6. In combination, a casing having a movable cover, a contact carried by the cover, a safety device in the casing including a resistance coil, a releaser pin electrically connected to the coil and adapted to engage the cover contact, a circuit including the coil and adapted to having its leads short circuited by the pin engaging the contact, and fusible means holding the pin inoperative, 105 said contact being removed from the path of the pin upon opening the cover.

In testimony whereof I affix my signature.

OTTO DREYER.
